[57] CLAIM

The ornamental design for a children's play seat, as shown and described.

DESCRIPTION

FIG. 1 is a right front perspective view of a children's play seat showing my new design;

FIG. 2 is a right side elevational view thereof, the left side being a mirror image of the right side;

FIG. 3 is a front elevational view thereof;

FIG. 4 is a rear elevational view thereof;

FIG. 5 is a top plan view thereof;

FIG. 6 is a bottom plan view thereof; and,

FIG. 7 is a view similar to FIG. 1 showing the play seat in its other operative position.
